UNITED STATES PATENT OFFICE.

ALLEN H. KERNGOOD, OF BALTIMORE, MARYLAND, ASSIGNOR TO ALMA MANUFACTURING COMPANY OF BALTIMORE CITY, OF BALTIMORE, MARYLAND, A CORPORATION OF MARYLAND.

SLIDING-TONGUE BUCKLE.

Application filed April 20, 1922. Serial No. 555,660.

To all whom it may concern:

Be it known that I, ALLEN H. KERNGOOD, a citizen of the United States, residing at Baltimore, in the State of Maryland, have 5 invented a certain new and useful Improvement in Sliding-Tongue Buckles, of which the following is a full, clear, and exact description.

This invention relates to that type of 10 buckles known as sliding-tongue buckles, as distinguished from pivoted-tongue buckles, and used on straps for garments and other articles, and the object of the invention is to provide an improved construction of sliding-tongue which may be economically made 15 and assembled, and which is held in place and guided in operation by connection with the frame of the buckle and serves to engage the adjustable end of the strap between its self and an adjacent portion of the frame; the tongue or slide member and the frame being so constructed and of such relative proportions and so assembled that both the slide and the frame are practically devoid of obtrusive elements or members, and hence the 20 tongue itself may be appropriately designated a level slide and the buckle as a whole may equally appropriately be termed a level slide buckle.

The invention consists of a sliding-tongue buckle having a frame of suitable construction and adapted to be permanently connected with one end or portion of a strap, and having a cross bar which is engaged by 25 a fold of the tongue in such way as to limit the movement of the tongue, and this cross bar and adjacent portions of the frame serve to guide the tongue, the tongue having its biting edge suitably formed to frictionally 30 or otherwise engage the free or adjustable end of the strap, in the forward movement of the tongue, as I will proceed now more fully to explain and finally claim.

In the accompanying drawings illustrating 35 the invention, in the several figures of which like parts are similarly designated, Figure 1 is a top plan view; Fig. 2 is a bottom plan view, and Fig. 3 is a longitudinal section of one form of the buckle of this invention. Fig. 4 is a perspective view of the frame alone. Fig. 5 is a perspective view of the tongue alone.

The frame 1 may be of any suitable form or configuration adapted to the uses for

which the buckle is designed, and preferably 55 is rectangular in general outline, and has the side bars 2, the front and rear bars 3 and 4, respectively, the depressed rear cross bar 5 to which is fixed one end of the strap and the depressed forward cross bar 6, the depression of which may be and preferably is slightly less than the depression in the rear cross bar 5.

The sliding-tongue 7, as shown in detail 60 in Fig. 5, is of sheet metal, having the transversely slotted leading or forward end 8, the rear edge 9 of which is made as an upstanding lip, which may be plain or toothed or otherwise formed to get a secure grip upon the strap and for stop purposes. This forward end 8 of the tongue has the cross member 10 and the laterally extended side members 11, which, as shown by dotted lines in Fig. 1 and full lines in Fig. 2, underlie the adjacent portions of the frame, so as to aid 70 in preventing the possibility of the tongue tilting on its supporting member and also so as to ease and guide the sliding movement of the tongue. This tongue is formed with a rear extension which is folded forwardly 75 upon itself as indicated at 12, about the forward cross bar 6. Preferably this folded portion of the tongue is of substantially the width of the inside of the frame, so that the tongue in its longitudinal movements will be 80 guided and steadied by the frame and supporting cross bar. The loop formed by the folded portion of the tongue serves also in part to limit the movement of the tongue and in any case insures the retaining of the 85 tongue in engagement with the frame no matter what strain is placed upon it. The upturned edge 9 of the tongue is sufficiently elevated to play in the plane of the frame, and by coming into contact with the cross 90 bar 3 of the frame to prevent the escape of the tongue from the frame in that direction. It will also be noticed that the forward end 8 of the tongue is in a lower plane than the top portion of the folded or loop-like rear 100 end 12 of the tongue. The drop 13 between these two parts serves as a stop to prevent undue rearward motion of the tongue on the cross bar 6 and also serves to practically close the forward end of the loop against escape of the tongue from said cross bar 6.

Not only is forward movement of the tongue limited by the upstanding edge 9, but it is

also limited by the engagement of the part 14 of the loop 12 with the rear edge of the cross bar 6.

The slotted leading end of the tongue and 5 the space between the cross bar 6 and the front bar 3 of the frame permits the passage of the adjustable end of the strap to be engaged by the tongue, and this free end of the strap is then tucked under the rear cross bar 10 4 if necessary or desirable.

The construction shown and described provides a very flat or thin buckle, and admits of economical manufacture.

Variations in the details of construction 15 and arrangement of parts are permissible within the principle of the invention and the scope of the claims following.

What I claim is:—

1. A sliding-tongue buckle, having a 20 frame provided with a front end bar and an adjacent cross bar, and a sliding tongue provided with a rearward extension folded forwardly and forming a loop which encloses the cross bar, whereby the tongue is secured 25 to the frame and adapted to be freely moved thereon forwardly and backwardly to respectively engage and disengage the strap end, the forward end of said tongue having a transverse slot through which the strap end 30 is passed and cooperating with the front end bar of the frame to engage the strap end.

2. A sliding-tongue buckle, having a 35 frame provided with a front end bar and an adjacent cross bar, and a sliding tongue provided with a transversely slotted strap-engaging end and a rearward extension folded forwardly and forming a loop which encloses the cross bar, whereby the tongue is secured to the frame, said loop being of substantial 40 the same width as the interior distance between the side bars of the frame and freely movable forwardly and backwardly on the cross bar.

3. A sliding-tongue buckle, having a frame provided with a front end bar and an 45 adjacent cross bar, and a sliding tongue provided with a transversely slotted strap-engaging end and a rearward extension folded forwardly and forming a loop which encloses 50 the cross bar, whereby the tongue is secured to the frame, said folded extension running lengthwise of the tongue toward the slotted end and having a drop at its forward portion so that the cross bar is engaged at front and rear to limit the movements of the 55 tongue.

4. A sliding-tongue buckle, having a frame provided with a front end bar and an adjacent cross bar, and a sliding tongue provided with a loop enclosing the cross bar and 60 thereby secured to the frame, said tongue having a transversely slotted leading end extending laterally on both sides of the frame and underlying the said frame, the loop and the slotted leading end being connected by 65 a dropped portion of the metal of the tongue which serves also to close the loop at its forward end about the cross bar.

5. A sliding-tongue buckle, having a frame provided with a front end bar and an 70 adjacent cross bar, and a sliding tongue provided with a loop enclosing the cross bar and thereby secured to the frame, said tongue having a slotted leading end underlying the frame and adapted to engage and hold the 75 adjustable end of a strap, said front end having a transversely arranged upstanding lip the edge of which extends up into the frame and between its sides.

In testimony whereof I have hereunto set 80 my hand this 19th day of April A. D. 1922.

ALLEN H. KERNGOOD.
